UNITED STATES PATENT OFFICE.

WALTER EVERETT MOLINS, OF DEPTFORD, LONDON, ENGLAND.

CIGARETTE MACHINERY.

Application filed April 18, 1927, Serial No. 184,811, and in Great Britain May 17, 1926.

This invention is for improvements in or relating to cigarette making machines and more particularly to a tipping and/or printing mechanism for use on a cigarette making machine of the continuous rod type, and it has for its object the provision of a tipping and/or printing mechanism so connected to the driving mechanism of the machine as to permit of free and easy access to all the driving mechanism.

The present invention consists of a tipping and/or printing mechanism for use on a cigarette making machine of the continuous rod type which comprises a plate or frame (arranged to carry the tipping and/or printing units) adapted to be hinged or equivalently mounted upon the machine to permit the movement of the same towards or away from the frame of the machine and simultaneously ensure that the tipping and/or printing units are operatively connected or disconnected from the drive of the machine.

The invention is more particularly described with reference to the accompanying drawings, in which:—

Fig. 1 illustrates in side elevation a tipping and printing mechanism constructed according to the present invention.

Fig. 2 is a plan view of Fig. 1, and

Fig. 3 is a detailed view of the means of operating the doctor blades of the various units.

Referring to the drawings the invention will hereinafter be described with reference to a combined tipping and printing mechanism wherein the tipping unit comprises the device described in Specification No. 251,322, and the printing unit comprises the device described in Specification No. 18,327 of 1925.

The gumming and printing rollers 1, 2 and 3 of the tipping and printing units are mounted upon a plate or frame 4, in such a manner that the spindles 5, 6 and 7 carrying the respective rollers extend through the plate or frame in a direction normal to the surface thereof, in such a manner that the various rollers are arranged on one side of the plate or frame 4 in correct spaced relationship, and the spindles which carry the same extend beyond the opposite face of the plate or frame and rotate in suitable bearings 15, 16 and 17. The spindles 5, 6 and 7

carry gear wheels 8, 9 and 10 at the free ends thereof. The gear wheels 8, 9 and 10 intermesh with gear wheels 11, 12 and 13 mounted upon a main spindle 14 supported in bearings 18 and 19 so that the axis thereof lies parallel to the surface of the plate or frame. The main spindle 14 drives an eccentric 20 which effects the longitudinal movement of the doctor blade 21, 22 and 23 through the agency of an eccentric rod 24 and lever 25, 26 and 27.

The main spindle 14 is provided at one end with a disc 28 having a slot or hole 29 formed in the face thereof. The plate or frame 4 upon which the tipping and printing units are mounted is supported upon the frame of the cigarette machine by hinges 30 which permit the said plate or frame to be swung into a position substantially flush with one face of the machine bed.

When the plate or frame is in this position the disc 28 mounted upon the main spindle 4 is located within the bed of the machine, and in contact with a second disc 31 driven from the main drive of the machine. The second disc 31 is provided (upon the face thereof which lies adjacent to the disc 28) with a yieldingly controlled pin 32 which is adapted to register with the slot 29 formed in the first disc, so as to provide a positive and automatic connection between the two discs and permit the tipping and printing units to be driven by the main drive of the machine in unison with the rod cutting mechanism of the cigarette making machine so as to ensure that the printing and tipping always occur at the same portion 85 of the rod relatively to where the cut takes place.

When the plate or frame is swung away from the bed of the machine the discs 28 and 31 hereinbefore referred to are separated, and the tipping and printing units are disconnected from the main drive of the machine.

Although the invention hereinbefore set out has been described with reference to the tipping unit described in Specification No. 251,322 and the printing unit described in Specification No. 18,327 of 1925, it will be appreciated that other forms of tipping and printing units may be used without departing from the spirit of the present invention, although the tipping and printing units set

forth in the specifications referred to are particularly suitable for such a construction on account of their compact nature.

What I claim as my invention and desire 5 to secure by Letters Patent is:—

1. A printing mechanism for use on a cigarette making machine of the continuous rod type which comprises a frame (arranged to accommodate the printing units) adapted 10 to be swingly mounted to permit the movement of the same relatively to the frame of the machine, and means operable solely by the movement of the frame to effect both the operative connection and disconnection of 15 the printing units with and from the drive of the machine and ensure that the printing units are always connected in correct phase relationship with the rod cutting mechanism.
2. A printing mechanism for use on a cigarette making machine of the continuous rod type which comprises a frame (arranged to accommodate the printing units) adapted 20 to be hinged to the frame of a machine to permit the movement of the same relatively 25 thereto, and a pin and slot connection arranged between the driving mechanism of the printing units and the main drive of the machine so as to ensure that the said units are automatically connected to the main 30 drive of the machine solely by the hinged movement of the said frame in such a man-

ner as to run in correct phase relationship with the rod cutting mechanism of the machine

3. In a printing mechanism for use on a cigarette making machine, the combination 35 with a shaft for driving printing and tipping units, of a support for said shaft and units shiftable to move said units into and out of operative position, a second shaft 40 driven from the cigarette making machine, and means for connecting said shafts operable by movement of said support and units into operative position.

4. In a printing mechanism for use on a cigarette making machine, the combination 45 with a shaft for driving printing and tipping units, of a support for said shaft and units shiftable to move said units into and out of operative position, a second shaft 50 driven from the cigarette making machine, and means effective to connect said shafts in a single relative angular position only on movement of said support and units into 55 operative position, whereby the correct phase relationship between the printing mechanism and the rod cutting mechanism of the machine is maintained.

In testimony whereof I hereunto affix my signature.

WALTER EVERETT MOLINS.
